US00D619632S

(12) **United States Design Patent**
Feng

(10) **Patent No.:** **US D619,632 S**
(45) **Date of Patent:** **** Jul. 13, 2010**

(54) **MANIPULATOR**

(75) Inventor: **Yong Feng**, Shenzhen (CN)

(73) Assignee: **Hon Hai Precision Industry Co., Ltd.**,
Tu-Cheng, Taipei Hsien (TW)

(**) Term: **14 Years**

(21) Appl. No.: **29/350,622**

(22) Filed: **Nov. 20, 2009**

(30) **Foreign Application Priority Data**

Sep. 15, 2009 (CN) 2009 3 0316101

(51) **LOC (9) Cl.** **15-99**

(52) **U.S. Cl.** **D15/199**

(58) **Field of Classification Search** D15/199;
D21/578; 74/490.01, 490.03, 490.05; 414/735;
700/245; 901/28

See application file for complete search history.

(57) **CLAIM**

The ornamental design for a manipulator, as shown and described.

DESCRIPTION

FIG. 1 is a perspective view of a first operative position of a manipulator showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a second operative position of the manipulator in a front elevational view thereof; and,

FIG. 9 is a third operative position of the manipulator in a front elevational view thereof.

The broken lines are for illustrative purposes only and form no part of the claimed design.
